CONTAINER

Morris W. Kuchenbecker, Neenah, Wis., assignor to
American Can Company, New York, N.Y., a corpora-
tion of New Jersey

Filed Sept. 26, 1962, Ser. No. 226,204
9 Claims. (Cl. 229—17)

The present invention relates to a self-sustaining carton or container and a unitary blank therefor, for the packaging and dispensing therefrom of flowable products such as liquids, granulated substances and the like and has particular reference to a top end closure which includes a conveniently available dispensing means and a handle for carrying the container.

This application is a continuation-in-part of my application Serial No. 853,366 filed November 16, 1959.

An object of the invention is to provide a top end closure for a container made from a unitary blank of paperboard or the like material wherein the closure includes a handle and a dispensing means which can be quickly and easily opened to dispense the container contents and which provides a convenient reclosure.

Another object is to provide a top end closure of the handle type which permits of the stacking of containers in vertical relation.

A further object is to provide such a top end closure which can be tightly sealed to preclude leakage of liquid contents from the sealed container.

Still a further object is to provide such a top end closure in which the movement to the opened dispensing position is facilitated.

Numerous other objects and advantages of the invention will be apparent as it is better understood from the following description, which, taken in connection with the accompanying drawings, discloses a preferred embodiment thereof.

Referring to the drawings:

FIG. 1 is a plan view of a unitary blank from which a container embodying the instant invention may be made;

FIG. 2 is a perspective view of a sealed container made from the blank shown in FIG. 1;

FIG. 3 is a perspective view of a partially formed container, the view showing how the blank is folded to form the container body;

FIGS. 4 and 5 are perspective views of the upper end of the container, the views showing how the top closure is formed;

FIG. 6 is a perspective view of the upper end of the container and showing how the sealed closure is opened;

FIG. 7 is a perspective view of the fully opened container with its dispensing device in dispensing position;

FIG. 8 is a schematic view shown at reduced scale and illustrating how the containers can be stacked;

FIG. 9 is a partial view of a unitary blank for making the container of the present invention showing a modified tab structure and added crease lines to facilitate the movement of the top closure to the opened dispensing position;

FIG. 10 is a partial side view of the upper end of a container made from the blank of FIG. 9 with the handle section broken away and showing how the top closure is formed and sealed; and

FIG. 11 is a perspective view of the upper end of the container of FIG. 10 showing the container in the opened dispensing position.

As a preferred and exemplary embodiment of the invention, the drawings disclose a substantially rectangular container comprising a body 11 (FIG. 2), a bottom 12 and a top end closure 13 which includes a carrying

2

handle 14 and a dispensing device 15 (see also FIG. 7) made from a single or unitary paperboard blank 16 (FIG. 1) of generally rectangular configuration.

The blank 16 (FIG. 1) is suitably cut and scored or creased to divide it into a number of walls, panels and tab portions. Four main side walls 21, 22, 23, 24 are respectively separated from each other and hingedly connected together along crease lines 25, 26, 27. A glue flap 28 is hingedly connected along one side edge of wall 24 by a crease line 29. The glue flap 28 is divided by crease lines 31, 32 into glue flap portions 33, 34, 35.

The bottom 12 of the container may be formed in any suitable manner. By way of example, the drawing of the blank shows four bottom closure flaps 36, 37, 38, 39 respectively connected to the container side walls 21, 22, 23, 24 along crease lines 41, 42, 43, 44. The bottom flaps are separated by cut lines 46, 47, 48, 49.

The top end closure 13 for the container comprises a pair of top panels 51, 52 and a pair of end panels 53, 54. These panels are hingedly connected to the respective side walls 21, 23, 22, 24 along hinge crease lines 56, 58, 57, 59 respectively.

The top panels 51, 52 are rectangular in configuration and are connected to the end panels 53, 54 and to the glue flap portion 35 along hinge crease lines 61, 62, 63, 64 which are extensions of the body wall crease lines 25, 26, 27, 29 respectively. Each of these top panels 51, 52 are divided by a pair of diagonal crease lines 66, 67, into three triangular sections 68, 69, 70. Along their top edges, the top panels 51, 52 are formed with rectangular handle tabs or sections 72 which are hingedly connected to the panels along crease lines 73. These handle sections 72 are provided with an angularly disposed crease line 74 which extends from the panel crease line 67 as shown in FIG. 1. The handle sections 72 also are formed with a potential finger hole defined by an incomplete circular cut line 75 which holds a plug 76 temporarily attached to the handle section but which may be punched out to provide a finger hole. One of the handle sections 72 is provided with a flap 77 which extends the full width of the section along a crease line 78. This flap is divided by a perforated line 79 into a fixed or glue flap portion 81 and a loose portion 82.

The end panels 53, 54 are each divided by diagonal crease lines 84, 85 into a triangular section 86 and a pair of triangular wing sections 87. The triangular sections 86 are hinged along the crease lines 57, 59 of the respective body side walls 22, 24 while the wing sections 87 are hinged along the diagonal crease lines 84, 85 and the body wall crease lines 61, 62, 63 and the glue flap crease line 64.

Above these triangular sections, the end panel 53 is provided with a rectangular tab 89 which is hinged to the panel 53 along a crease line 91. The tab 89 is disposed between the two handle sections 72 and is separated therefrom by cut lines 92. A longitudinal perforated tear line 93 divides the tab 89 into a fixed tab portion 94 and a loose tab portion 95 for a purpose to be hereinafter explained.

The end panel 53 and its tab 89 constitute elements of the conveniently available pouring spout or dispensing means 15 hereinbefore mentioned. To facilitate formation of this dispensing means in a finished container the blank is provided with a transverse crease line 96 which extends across the tab 89 and the end panel 53 and into the body side wall 22 where it terminates and joins with a pair of diagonal crease lines 97 defining a triangular section having a base crease line 42 as shown in FIG. 1.

The end panel 54 is provided with a projecting tab 101 which is hingedly connected to the panel along a crease line 102 and is separated from the adjacent handle section 72 by a cut line 103. This tab 101 is transversely divided into two sections 104, 105 by a crease line 106 and each

section is formed with a potential finger hold defined by an incomplete circular cut-line 107 which holds a plug 108 temporarily in place. These potential finger holes are located in a predetermined relation to the potential finger holes in the handle sections 72 so as to align with them when the blank 16 is folded along its various crease lines to produce the container shown in FIG. 2.

In order to produce the container shown in FIG. 2 the blank 16 is first folded along the side wall crease lines 25, 26, 27 and glue flap crease line 29 to form the rectangular body 11 as best shown in FIG. 3, the side walls 21, 22, 23, 24 being tied together by the glue flap portion 34 which is bonded by a suitable adhesive to the inner face of the side wall 21 along its free edge. The glue flap portion 35 is also bonded to the top panel 51 along its free edge. The four bottom flaps 36, 37, 38, 39 and the glue flap portion 33 are then folded in the usual manner into overlapping position perpendicular to the side walls, along their respective crease lines 41, 42, 43, 44 and are adhesively secured together to form the bottom 12 of the container. This is a conventional bottom construction.

In this open top end condition, with the body 11 and the bottom 12 fully formed, the resulting container is ready for filling. For liquid products the open end container is usually immersed in or otherwise coated with molten wax or other liquid-proofing substance to render the container leak-proof.

The filled container is closed and sealed by folding the top panels 51, 52 inwardly and the end panels 53, 54 outwardly as shown in FIG. 4. The folding of the top panels 51, 52 inwardly hinges them on their respective crease lines 56, 58 and also bends the handle sections 72 along their crease lines 73, so that the two handle sections 72 are in an upright juxtaposed relation as shown in FIG. 4.

The outward folding of the end panels 53, 54 hinges them on their respective crease lines 57, 59 and collapses the panels so that the triangular wing sections 87 fold along their diagonal crease lines 84, 85 into place against the back of the triangular section 86. Simultaneously with this wing folding section, the tab 89 of the end panel 53 hinges along its crease lines 91, 96 to fold the tab back on itself in a double thickness relation and to locate the folded tab in an upright position adjacent one end of the juxtaposed handle sections 72. In a similar manner the tab 101 on the end panel 54 hinges along its crease lines 102, 106 to fold the tab portions 104, 105 into a contiguous relation and to locate these tab portions in an upright position adjacent the other end of the juxtaposed handle sections 72 as shown in FIG. 4.

With the tabs 89, 101 of the respective end panels 53, 54 in the positions shown in FIG. 4, the panels are bent upwardly along their crease lines 57, 59 into a position surmounting the top panels 51, 52. This action interposes the tabs 89, 101 into the space between the upright handle sections 72 as shown in FIG. 5. In this position the tab 101, the fixed portion 94 of the tab 89, and the handle section 72 are adhesively bonded together in a permanent joint. The flap 77 of one of the handle sections 72 projects above the other handle section and is hinged downwardly along its crease line 78, over this other handle section and its glue portion 81 is adhesively secured in place, the loose portion 82 of the flap remaining free but in folded-over position as a coextensive part of the adhesively bonded portion as shown in FIG. 2. There thus results a tight top closure for the container, with the potential carrying holes in alignment and ready for use in carrying the container, and with the top panels 51, 52 in a horizontal position which permits of the stacking of a plurality of such containers as best shown in FIG. 8.

To open the container, it is merely necessary to tear the loose flap portion 82 free of the adhesively bonded portion 81, along its tear line 79, as shown in FIG. 6. The end panel 53 is then pulled out to the position shown in FIG. 4. This action breaks the loose tab portions 95 free of the adhesively bonded tab portions 94 of the tab 89,

the break being effected along the tear line 93. The handle sections 72 are then pulled up and this expands the end panel 53 and the side wall 22 connected thereto, along their crease lines 84, 85, 57, 96, 97, 91 and bulges the top panels 51, 52 along their crease lines 66, 67, 74 to provide the pouring spout or dispensing device 15 as shown in FIG. 7.

After a dispensing operation, the container may be readily reclosed by pressing the expanded end panel 53 and side wall 22 back to their unexpanded flat positions and simultaneously pressing the handle portions 72 downwardly to return the top panels 51 and 52 to their original flat configuration. The end panel 53 may then be moved upwardly about the crease line 57 to reposition the loose tab portions 95 into the space between the handle sections 72 as shown in FIG. 6.

In the form of the instant invention shown in FIGS. 9 through 11, the tabs 89 and 101 have a modified structure which provides improved sealing against leakage through the top closure of liquids packaged in the container. As shown in FIG. 9, the tab 89 of the blank 16 is provided with stepped portions 109 at the upper free edge of the tab adjacent the cut lines 92. The stepped portions 109 have edges 110 disposed at an angle to the transverse axis of the blank, preferably at right angles thereto as shown. The tab 101 is similarly provided at its upper free edge with stepped portions 111 having edges 112 adapted for mating engagement with the stepped portions 109 of the tab 89 when the container is erected.

The tab 89 is divided by weakened tear lines 113 into two trapezoidal shaped loose tab portions 114 and a fixed tab portion 115. The loose tab portions 114 are symmetrically shaped and symmetrically disposed on each side of the crease line 96 with the longer parallel side of each trapezoidal shaped loose tab portion being formed by a portion of the crease line 91 and with the loose tab portions abutting each other at the crease line 96. The portions of the tear lines 113 forming the sides of the loose tab portions 114 adjacent the cut lines 92 are spaced from the cut lines 92 to provide the fixed tab portion 115 with projections extending to the crease line 91 between the loose tab portions and the cut lines 92.

The modified form of the blank 16 shown in FIG. 9 is formed into a container in a similar manner as heretofore described for the preferred embodiment of the blank shown in FIG. 1. In the erected container, the tabs 89 and 101 are interposed between the handle sections 72 with the upper free edges of the tabs including the stepped portions 109 and 111 and the edges 110 and 112 of the tabs 89 and 101 respectively disposed in contiguous relation (FIG. 10). The tab 101 and the fixed portion 115 of the tab 89 are adhesively bonded to the handle sections 72 with the adhesively bonded area running the full length of the handle sections adjacent the bottom edge of the handle sections and fully including the stepped portions 109 and 111 of the tabs. With the fixed tab portion 115 of the tab 89 extending fully to the crease line 91 and the adhesive bond between the handle sections 72 and the tabs 89 and 101 thereby extending the full length of the handle sections, the possibility of leakage occurring at the corner juncture of the top panels 51, 52, handle sections 72 and tabs 89 and 101 is effectively precluded.

During the adhesive bonding of the tab 101 and the fixed portion 115 of the tab 89 to the handle sections 72, an upward force is exerted on the tab 89 and a downward force is exerted on the tab 101, the forces being of sufficient magnitude to maintain the edges 110 and 112 in close abutting engagement. In the formed top closure 13, the adhesively bonded abutting edges 110 and 112 produce a tight leakage proof seal along this portion of the contiguous edges of the tabs 89 and 101. The effect of dimensional variations in the tabs 89 and 101 which could result in their contiguous edges failing to

abut at any portion of their length thereby making possible the presence of a fine leakage path therebetween is thus overcome, and greater dimensional tolerances can be employed with consequent savings in manufacturing costs.

After the tab 101 and the fixed portions 115 of the tab 39 have been adhesively bonded to the handle sections 72, the flap 77 of one of the handle sections which projects above the other handle section is hinged downwardly along its crease line 78 over this other handle section (FIG. 10) and adhesively secured to this other handle section along its full length.

The modified form of the container shown in FIG. 10 is opened by merely pulling the end panel 53 outwardly to break the loose tab portions 114 free of the fixed tab portion 115 along the tear lines 113. This also causes the fixed tab portion 115 to be separated from the triangular wing section 87 of the end panel 53 by rupture of the portions of the crease line 91 along which the projections of the fixed tab portion are joined to the wing sections. The handle sections 72 are then pulled upwardly bulging the top panels 51 and 52 along their crease lines 66, 67, 74 and expanding the end panel 53 and the side wall 22 along their crease lines 84, 85, 57, 91, 95 and 97 to provide the pouring spout or dispensing device 15 as shown in FIG. 11.

Where a stiff grade of paperboard is used such as may be required in making a larger size container, e.g. a one gallon size, it has been found desirable to provide one or more crease lines 116 adjacent each end of the crease line 57 joining the end panel 53 and side wall 22 to facilitate the expansion of the end panel 53 and the side wall 22 in the formation of the dispensing spout 15 when the container is opened. The crease lines 116 extend angularly outwardly from the crease lines 84, 85 defining the upper edges of the end panel 53 across the crease line 57 to the crease lines 25, 26 defining the longitudinal edges of the side wall 22.

After a dispensing operation the container may be readily reclosed in a similar manner as heretofore described.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A top end closure for a self-sustaining tubular container having a body portion defined by four substantially rectangular side walls, said top end closure comprising a pair of top panels extending from a first pair of oppositely disposed side walls and projecting substantially in the same plane in opposite directions across and closing the top end of said container body portion, a handle section on each of said top panels, said handle sections being disposed in upright and juxtaposed relation, a pair of end panels extending from the remaining pair of oppositely disposed side walls and formed integral with and surrounding said top panels, said end panels being disposed adjacent the end edges of said top panels and said handle sections, and tab portions integral with and extending from said end panels, said tab portions having terminal edges with the terminal edges of the tab portions of one

of said end panels being contiguous the terminal edges of the tab portions of the other of said end panels, said contiguous edges adjacent said top panels being non-linear with at least a part of said contiguous terminal edges of said tab portions being in abutting engagement, said part thereof in abutting engagement being disposed at an angle to the longitudinal axis of said container, said tab portions of said one of said end panels being secured to said handle sections, said tab portions of said other of said end panels being divided by a tear line into fixed tab portions secured to said handle sections and loose tab portions, said tear line being rupturable by an outward pull on said other of said end panels to separate said loose tab portions from said fixed tab portions whereby said other of said end panels and said loose tab portions may be displaced outwardly from said top end closure for use as a dispensing means for said container.

2. A top end closure of the character defined in claim 1 wherein said angle is substantially a right angle.

3. A top end closure of the character defined in claim 1 wherein said tab portions are interposed between said handle sections.

4. A top end closure of the character defined in claim 1 wherein said handle sections and said tab portions of said one of said end panels are provided with aligned finger holes for carrying said container.

5. A top end closure of the character defined in claim 1 wherein said end panels are of triangular configuration and are formed with triangular wing sections disposed contiguous with said triangular panel and are hingedly connected to said panels, and wherein said tab portions are hingedly connected to said wing sections.

6. A top end closure of the character defined in claim 1 wherein the lowermost part of said loose tab portions is spaced above the plane of said top panels and separated therefrom by said fixed tab portions.

7. A top end closure of the character defined in claim 1 wherein said dispensing means includes weakened crease lines in said other of said end panels and its integrally joined side wall, said crease lines comprising a longitudinal crease line extending downwardly from the uppermost edge of said other of said end panels continuing into said integrally joined side wall, a pair of downwardly diverging crease lines in said side wall extending from said longitudinal crease line, and diagonal crease lines extending from the upper edges of said other of said end panels across the line of juncture of said other of said end panels and said side wall to the side edges of side wall whereby said side wall and said other of said end panels are deformable into a trough-like structure by inward pressure on said first pair of oppositely disposed side walls.

8. A top end closure of the character defined in claim 7 having a pair of spaced diagonal crease lines disposed adjacent each end of the line of juncture of said other of said end panels and said side wall.

9. A top end closure of the character defined in claim 7 wherein said top panels are provided with crease lines to facilitate formation of said trough-like structure of said dispensing means.
